NICHOLAS S. VEDDER, OF TROY, AND TOBIAS S. HEISTER, OF LANSINGBURG, NEW YORK, ASSIGNORS TO NICHOLAS S. VEDDER.

Design No. 3,326, dated January 5, 1869.

DESIGN FOR THE PLATES OF A STOVE.

The Schedule referred to in these Letters Patent and making part of the same.

---

o all whom it may concern:

Be it known that we, NICHOLAS S. VEDDER, of Troy, and TOBIAS S. HEISTER, of Lausingburg, in the county of Rensselaer, and State of New York, have jointly invented or produced a new and original Design for Plates of a Box-Stove, called the "Crystal," of which the following is a full and exact description, reference being had to the accompanying photographs, in which—

Figures 1 and 2 are perspective views of a box-stove, aving our said design.

Like parts are marked by the same letters in both figures.

Our new design for the side-plates A consists of the compound ornament b c d on the panel e, surrounded by the ornamental moulding f, with vine-like ornaments outside, at the corners, and all shaped and arranged so as to appear as represented in fig. 1; and

The design for the ends or plates H consists of the central ornament i j k, on a swelling surface l, with arched ornamentalations m n o at top and bottom, all shaped and disposed so as to present the appearance represented in the aforesaid photographs.

What we claim as our invention or production, and desire to secure by Letters Patent, is—

The design for plates of a box-stove, herein shown and described.

In testimony whereof, we have hereunto set our hands, this 8th day of December, A. D. 1868.

NICHOLAS S. VEDDER.
TOBIAS S. HEISTER.
